UNITED STATES PATENT OFFICE.

ALFRED GRASS, OF NEW YORK, N. Y., ASSIGNOR TO AMERICAN CAN COMPANY, OF NEW YORK, N. Y., A CORPORATION OF NEW JERSEY.

MASTER SHEET FOR USE IN MAKING LITHOGRAPHIC PRINTING SURFACES AND METHOD OF MAKING THE SAME.

1,416,706.

Specification of Letters Patent. Patented May 23, 1922.

Application filed June 8, 1918. Serial No. 238,970.

To all whom it may concern:

Be it known that ALFRED GRASS, citizen of Great Britain, residing at New York, in the county of New York (#467 West 22d St.) and State of New York, has invented certain new and useful Improvements in Master Sheets for Use in Making Lithographic Printing Surfaces and Methods of Making the Same, of which the following is 10 a specification.

This invention relates to the production of a translucent or transparent master sheet for use in the preparation of printing surfaces, and has for its objects to simplify and 15 cheapen and greatly improve the qualities of such surfaces or plates, and also the printing process, and to provide for permanently preserving the text, pictorial or other composition which has been printed, in such 20 form that it can be used again repeatedly to produce additional printing plates, registering in each instance the same clear and well defined photo impression on sensitized lithographic (metal or stone) surfaces as 25 was produced on the first printing surface, and also producing flexible master sheets for color work that can be stored away and used at any future time and give perfect register for 30 the different color plates, the treatment of the translucent sheets rendering them so nearly moisture proof that there is no appreciable 35 change in their size or shape due to contraction or expansion incident to ordinary climatic changes, and which occupy a very 40 small space and may be conveniently filed or stored away as flat sheets safe from injury or deterioration.

With such objects in view, as well as other 45 advantages which may be incident to the use of the improvements, the invention consists in the procedure, and in the parts and combinations thereof hereinafter set forth and claimed, with the understanding that the several necessary elements constituting the same may be varied in proportions and arrangement without departing from the nature of the invention.

In order to make the invention more 50 clearly understood there are shown in the accompanying drawings means for carrying the same into practical effect, without limiting the improvements in their useful applications, to the particular constructions which, for the purpose of explanation, have

been made the subject of illustration. In 55 the said drawings—

Fig. 1 of the drawings represents a tissue impression sheet rendered transparent and carrying an impression.

Fig. 2 represents a backing sheet rendered 60 transparent on which impression sheets are mounted to make a master sheet as per dotted lines. One corner of one of the impression sheets is pulled over to show it more clearly.

Referring to the drawing, 1 represents a sheet of tissue paper or equivalent material that is preferably a paper known as silver tissue used for wrapping and packing silverware. This is coated on both sides with 70 a composition consisting of approximately five parts of translucent varnish, one part of translucent oil such as boiled linseed oil and two and one-half parts of turpentine or its equivalent, the indicated proportions being somewhat varied to secure proper drying, whether the air be more or less charged with moisture, which sheet, when dried, will be translucent to a high degree, with a 75 smooth surface for receiving ink and adapted to be applied over a lithographic surface or plate having thereon a grained surface and a sensitive photographic film, so that the text, pictorial design or other matter contained on the sheet 1 may be printed by 80 light on the film of said plate. The matter which it is desired to print having been set up in type, the form of type is inked, and the sheet 1 is impressed thereon so that the entire text or other matter will appear on 85 the sheet, but it is first necessary to prepare the surface of the sheet for such impression by rubbing the same with an evenly comminuted powder such as talc, powdered magnesia or other equivalent. After said 90 impression has been made, the surface of the sheet is dusted with an opaque powder such as graphite, lamp black, bronze, silver or Indian red, which opaque powder will adhere to the ink of the impression and render 95 the same entirely opaque for the said light printing operation.

Then the excess of powder is dusted off, the talc, magnesia or its equivalent, rendering the sheet smooth and non-absorbative, so that no opaque powder 100 will remain excepting that adhering to the ink impression, and the sheet will be clearly translucent in contrast with the entirely

opaque character of the said impression or design thereon. The sheet 1, now called the impression, having said design or printing 3 thereon, is then coated with a suitable varnish by aid of an air brush so as not to blur or impair the design and so as to protect and make permanent any subsequent use of the inked and opaqued parts. A backing or 10 supporting sheet 2 of bond paper, or other suitable fibrous sheet material, is coated with a composition consisting of approximately equal parts of neat's-foot oil and turpentine or its equivalent, and is thoroughly dried. This sheet 2 forms a suitable mounting for a 15 plurality of the impression sheets 1 to produce thereby a large master sheet carrying a plurality of identical impressions for use as a printing medium in producing the lithographic printing surface. In mounting 20 the small impression sheets 1 on the large backing sheets 2, the side of each of the sheets coming in contact with another sheet is coated with a suitable thin volatile varnish, preferably an amel acetate mastic 25 varnish, when they are pressed together and squeegeed and left until set and dried. Any number of small designs can be set up on the large sheet, as shown by dotted lines on Fig. 2, and photographic film negatives 30 may be used interspersed with the printed matter if desired, and various features of printed matter may be combined together in thus producing the master sheet. The sheet 1 may be of the same size as sheet 2, 35 or sheet 1 may be used without mounting on a backing sheet, if the design is large enough to cover fully the size printing surface desired. In the production of the small impression sheets 1, a large sheet is preferably 40 treated with the oil and then cut up into smaller impression sheets to accommodate the area of the impressions to be mounted on the backing sheet to produce the multiple impression master sheet. The impression sheets 1 are usually applied to the sheet 2 with their printed surface up, so that the design surface comes in as close contact as 45 possible with the sensitive film of the lithographic surface when the photo printing is to be done so as to give the maximum sharpness. In applying photo films to a backing sheet 2 the emulsion film is first removed from a contrast stripping wet or dry plate, which has been suitably exposed and developed. 50 An important advantage of this invention resides in the easy and perfect manner by which what is called "resetting" may be accomplished. Resetting means readjusting or replacing the impressions 1 on a backing or 55 supporting sheet 2, giving the impressions a wider or narrower spacing as may be necessary to accommodate different sizes of sheets to be printed with the same design, or for master sheets from which to produce 60 plates for suitably printing the same design.

on flat material to be folded into other sizes of boxes or cartons. For instance, the same impression is frequently applied to the covers or sides of different size packages of the same class. If applied to a larger package 70 than the original layout was made for, it becomes necessary to increase the spacing of the impression sheets 1 on the backing sheet 2, and if applied to smaller packages than the original layout was intended for, 75 it becomes necessary to reduce the spacing of the impression sheets 1. I accomplish this result by taking the master sheet as originally laid out with the impressions 1 secured thereto and cut it up so that each 80 impression becomes again an individual impression sheet. These individual impressions are then mounted on a second backing sheet exactly similar to sheet 2 when a new master sheet is produced having the impressions spaced to suit the new requirements of printing, and since all of these sheets are translucent, the triple thickness of paper gives as perfect results in printing onto the litho plate as the double thickness master 85 sheets produce.

This invention is related to that described in my Patent 1,333,544, granted March 9, 1920, and the procedure may be such as set forth in said application, except as modified 95 according to my present improvements.

What is claimed is:

1. A translucent master sheet for the production of lithographic printing surfaces, comprising a fibrous sheet treated to render 100 it translucent and moisture resistant, and having thereon a design in light-obstructing color, said sheet being attached to a translucent backing sheet treated with neat's-foot oil and turpentine, said fibrous sheet and 105 backing sheet being adhered together to enclose said design.

2. A translucent master sheet, for the production of lithographic printing surfaces, consisting of a tissue sheet treated with 110 varnish, oil, turpentine and talcum powder and carrying opaque designs, and a mounting sheet treated with neat's-foot oil and turpentine, said sheets being adhered together to enclose said opaque designs by the 115 aid of a thin turpentine varnish.

3. A method of making master sheets for the production of lithographic printing surfaces, which consists in treating a tissue sheet with oil and a drier, treating a mounting sheet with neat's-foot oil and turpentine, applying opaque designs on said tissue sheet and adhering together said tissue sheet and said mounting sheet with said designs in contact with the adhered surfaces. 120

4. A method of making master sheets for the production of lithographic printing surfaces, which consists in treating a tissue sheet with varnish, boiled linseed oil and turpentine, drying the same, dusting the 125 130

same with talcum powder, applying an opaque design on said sheet, dusting said design with powdered lamp black, varnishing over the design by an air brush; treating a mounting sheet with neat's-foot oil and turpentine and drying the same, and adhering together said tissue sheet and said mounting sheet by the aid of a thin turpentine varnish.

10 5. A translucent master sheet for the pro-

duction of lithographic printing surfaces, consisting of an oiled and translucent tissue sheet having an opaque design applied thereto, and a translucent mounting sheet treated with neat's-foot oil and turpentine 15 and having said tissue sheet adhered thereto.

In testimony whereof I affix my signature.

ALFRED GRASS.
